CLAIM

The ornamental design for a rail member, as shown and described.

DESCRIPTION

FIG. 1 is a front top perspective view of a rail member.

FIG. 2 is a bottom rear perspective view of FIG. 1.

FIG. 3 is a front elevation view of FIG. 1.

FIG. 4 is a rear elevation view of FIG. 1.

FIG. 5 is a top side view of FIG. 1.

FIG. 6 is a bottom side view of FIG. 1.

FIG. 7 is a left side elevation view of FIG. 1; and,

FIG. 8 is a right side elevation view of FIG. 1.

The dash-dash lines represent portions of the rail member that form no part of the claimed design.

1 Claim, 6 Drawing Sheets
